Patented Jan. 31, 1922.

FIG. 1.

FIG. 2.

FIG. 3.

Inventor:
Edwin M. Watson.

by his atty *Charles D. Godwin*

UNITED STATES PATENT OFFICE.

EDWIN M. WATSON, OF BOSTON, MASSACHUSETTS.

AUTOMATIC MAGNETIC LOCK.

1,405,369.

Specification of Letters Patent.

Patented Jan. 31, 1922.

Application filed June 20, 1919. Serial No. 305,689.

To all whom it may concern:

Be it known that I, EDWIN M. WATSON, a citizen of the United States, residing at Boston, in the county of Suffolk and State 5 of Massachusetts, have invented new and useful Improvements in Automatic Magnetic Locks, of which the following is a specification.

This invention relates to automatic magnetic locks and is particularly designed to 10 be used in connection with doors and hatches leading to the boiler rooms of steam vessels particularly of the torpedo boat destroyer type which use oil for fuel, and because of the use of said fuel oil and the 15 necessity of providing at times a forced draft are obliged to keep the boiler rooms under air pressure.

Under these circumstances it is always 20 necessary to provide a double set of doors together with a small passage-way known as an "air lock" located therebetween for every entrance to the boiler room and it is necessary for anyone wishing to enter or 25 leave said boiler room to first enter said passage-way, always being certain before opening the first door that the door beyond is closed, and after having entered said passage-way to be sure that the first door is 30 closed before leaving the passage-way by the second door.

It is evident, therefore, that the occupants of the boiler room are always threatened with the possibility that both doors 35 leading to the boiler room may be carelessly opened at the same time, in which event the air within the boiler room will rush outwardly through said doors thereby causing a flare-back. This flare-back results from a draft coming down the smoke-stack instead of passing up the same, thereby drawing the flame from under the boilers out into the boiler room and thereby burning the occupants of said boiler room before 45 the flames can be controlled.

The object of the invention is to provide an automatic safety locking device for the doors above referred to, independent of other hand operated fastening devices, and 50 thereby make it impossible when one of the doors has been opened to open the other door.

The invention consists in the combination and arrangement of parts set forth in the

following specification and particularly 55 pointed out in the claims thereof.

Referring to the drawings:

Figure 1 is a diagrammatic representation of my improved mechanism, the same being illustrated in connection with two conventional doors.

Figs. 2 and 3 are detail views of a switch used in connection with my improved device.

Like numerals refer to like parts throughout the several views of the drawings.

In the drawings, A and B are two conventional doors. These doors may represent the doors of a passage-way or "air lock" leading to the boiler room of a vessel 70 which is obliged to have the boiler room under air pressure in order to provide a forced draft for the boilers.

Each of the doors A and B are provided with duplicate parts and duplicate electrical equipment, therefore the description of one of said doors applies equally well to the other.

Fast to the door A is a finger 5, said finger 5 constituting a means for simultaneously making or breaking an electric circuit in two places at a switch C thereby energizing or de-energizing a double coil electromagnet D which controls a bolt mechanism E provided for the door B.

The switch C illustrated in detail in Figs. 2 and 3 is fastened to a wall 6 adjacent to the door A in such a manner that when the door A is closed the finger 5 will engage a plunger 7 constructed of non-conductive 90 material which is fastened to a pair of contact members 8 and thereby force said contact members out of engagement with a second pair of conductors 9 mounted upon a casing 10. Terminals 11 connect with the 95 contact members 8.

Each contact member 8 is pivoted upon a bracket 12 which is fastened to a base plate 13 constructed of insulating material. A spring 14 normally tends to force the members 8 into contact with the members 9. An electric conductor 15 connects each bracket 12 with terminals 16 fast to the base plate 13. Wires 17 and 18 connect the terminals 15 with terminals 19 provided for the electro-magnet D which operates the bolt mechanism E of the door B.

An armature 20 is pivoted at 21 to a plate

22 which forms a base for the electro-magnet D in such a manner that when the electro-magnet D is energized, said armature will operate a bolt 23 connected thereto, said 5 bolt constituting a part of the bolt mechanism E of the door B.

The bolt 23 is mounted in a slide 24 and is adapted to engage a socket 25 fast to the door B at which time said door will be 10 locked.

When the electro-magnet D is de-energized a spring 26 will automatically pull the armature 20 against a stop pin 27 at which time the bolt 23 will be disengaged from the 15 socket 25 and the door B will be unlocked.

The terminals 11 connect through wires 28 and 29 with a suitable source of electric supply. Switches 30 and 31 are provided whereby said source of electric supply may 20 be cut off when desired as for example when the boiler room is not under pressure and it is not desired to use the safety device.

The operation of my improved automatic magnetic lock is as follows: If a person wishes 25 to enter or leave the boiler room, he approaches either of the doors A or B which in their normally closed position are both fastened by hand operated fastening devices, but are both unlocked as far as my automatic magnetic lock is concerned. In attempting to 30 open the door which is at first approached, if the door is found locked it indicates that the door beyond is open. If, however, on attempting to open door the door opens, the 35 opening of said door will close the electric circuit at the switch C adjacent to the door opened, which will energize the electro-magnet D and thereby operate the bolt mechanism E of the door which is beyond, thereby 40 locking said door. The door beyond cannot now be opened by anyone until the first door has been closed. When the first door has again been closed, the electric circuit will again be broken at the switch C 45 of said door thereby de-energizing the electro-magnet D of the door beyond and thereby automatically unlocking said door, which is then free to be opened. Simultaneously with the opening of the second door the 50 switch C will close the electric circuit to the electro-magnet D of the door first opened and thereby automatically operate the bolt mechanism E to lock said door which in turn 55 cannot then be opened until the second door is again closed, at which time both doors will become automatically unlocked. In attempting to enter or leave the boiler room

the operation of each door is exactly the same.

It should be understood that the term 60 "boiler room", as hereinbefore used, designates both the boiler room and the fireroom which generally are substantially one room being only separated by a grating. If, however, said rooms should happen to be separated by a solid flooring, the mechanism hereinbefore described would be used in connection with the fireroom.

Having thus specifically described my invention what I claim and desire by Letters 70 Patent to secure is:

1. A device of the character described having, in combination, a pair of doors, a sliding bolt for each door, an armature for each bolt pivotally mounted intermediate its 75 length and attached at one end thereof to its bolt, an electro-magnet adapted to operate each bolt respectively through its armature, a source of electric supply, and means operated by each door whereby when one of 80 said doors is opened the electric circuit to the electro-magnet of the closed door will be completed and said electro-magnet will be energized thereby operating its bolt directly through its armature whereby said 85 door will be automatically locked.

2. A device of the character described having, in combination, a pair of doors, a sliding bolt for each door, an armature for each bolt pivotally mounted intermediate its 90 length and attached at one end thereof to its bolt, an electro-magnet adapted to operate each bolt respectively through its armature, a source of electric supply, means operated by each door whereby when one of said doors 95 is opened the electric circuit to the electro-magnet of the closed door will be completed and said electro-magnet will be energized thereby operating its bolt directly through its armature whereby said door will be automatically locked, and a spring connected to the opposite end of said armature from 100 said bolt whereby when said opened door is again closed and the electric circuit is again broken thereby de-energizing the electro-magnet of the closed door, said closed door 105 will be automatically unlocked.

In testimony whereof I have hereunto set my hand in presence of two subscribing witnesses.

EDWIN M. WATSON.
